ADOLPH C. VAN SLUYS, OF NASHUA, NEW HAMPSHIRE, ASSIGNOR TO NASHUA GUMMED AND COATED PAPER COMPANY, OF NASHUA, NEW HAMPSHIRE, A CORPORATION OF MASSACHUSETTS.

METHOD OF AND APPARATUS FOR BREAKING THE DRIED COATING ON SHEET MATERIAL.

1,368,080.

Specification of Letters Patent.

Patented Feb. 8, 1921.

Application filed October 17, 1917. Serial No. 197,090.

To all whom it may concern:

Be it known that I, ADOLPH CHARLES VAN SLUYS, a subject of the Queen of Holland, and a resident of Nashua, in the county of Hillsborough and State of New Hampshire, have invented an Improvement in Methods of and Apparatus for Breaking the Dried Coating on Sheet Material, of which the following description, in connection with the accompanying drawings, is a specification, like characters on the drawings representing like parts.

This invention relates to methods of and machines for breaking the dried coating on thin sheet material so that such material will lie flat without curling, and further relates to the material produced by the use of such machines and methods.

While applicable in respect to many of its features to the treatment of sheet material other than paper, and to sheet material coated with substances other than adhesive gum, the invention has special application to the treatment of gummed paper, whereby the surface of the dried gummed coating is broken or cracked by minute lines of breakage, thereby reducing or eliminating the tendency of the paper to curl because of the shrinkage of the gum in drying.

The invention will be best understood by reference to the following description when taken in connection with the accompanying illustration showing one embodiment of the invention, while the scope will be more particularly pointed out in the appended claims:

In the drawings:

Figure 1 is a plan view of the principal working parts of a machine embodying one form of the invention;

Fig. 2 is a sectional elevation on the line 2—2 in Fig. 1 showing the same machine on a slightly enlarged scale;

Fig. 3 is a sectional elevation of the machine shown in Fig. 1 taken on the line 3—3 in Fig. 1; and

Fig. 4 is a sectional side elevation taken on the line 4—4 in Fig. 1.

Referring to the drawings, I have therein shown for illustrative purposes a gummed paper breaking machine embodying one form of the invention, provided with the

frame 1 on which is supported the breaking devices, together with guiding means and suitable devices for feeding the paper to the breaking devices and receiving the paper after the latter has been subjected to the breaking action.

While the broad features of my invention may be usefully employed for breaking the gum on severed or separated sheets, the machine herein is capable of breaking the gummed coating on a continuous strip or sheet of paper adapted to be fed progressively through the machine from the mill or supply roll 2 at one end of the machine to the reel or winder 3 at the opposite end of the machine.

Referring particularly to Figs. 1 and 3, the mill roll is supported in journals at one end of the frame 1, the sheet of paper designated as 4 passing from the mill roll over any suitable system of guide rolls such as the under roll 5 and the upper roll 6 to the friction rolls 7 and 8. The latter are preferably provided with means such as the helically arranged strips of felt 9, so that the paper in passing between the rolls may be frictionally engaged, and the rolls are preferably positively driven from any suitable source of power, as by a driving belt connected to the pulley 10, the rolls having intermeshing gears 10*. These rolls draw the paper from the mill or supply roll at a uniform rate and resist the draft under which the broken portion of the paper is drawn, so that a definite and uniform tension is developed in passing over the breakers. Other devices for feeding or tensioning the paper, however, may be employed, the described rolls being submitted for illustrative purposes.

From the friction rolls 7 and 8, the paper passes over breaking means so arranged that as the paper is fed, there is progressively developed a sharp bend transverse to the sheet, with the gummed coating on the outside of the bend. Preferably, though not necessarily, the breaking means is in the form of a stationary element presenting an edge or a corner to the back of the gummed paper, so that the latter is bent or deflected sharply about such corner in its path of travel. The exact shape of such breaking

element, as to its angularity or its sharpness, may be widely varied according to the intensity of the breakage required for different grades or thicknesses of paper or coatings of different character, the main requirement being that it shall produce a bend in the paper sharp enough to sufficiently crack the surface of the coating to oppose the tendency of the paper to curl.

10 Preferably the relation of the breaking means to the path of the paper is such that the bend in the paper, which develops the lines of break, lies obliquely across the length of the strip or the path of the paper, 15 so that the resulting cracks or breaks develop in a general direction also transverse and oblique to the length of the sheet. To effect this, the breaking member 11 (Figs. 1 and 3) is mounted upon the supporting 20 bracket 12 which rests upon the frame 1, and extends obliquely across the path of the paper, as seen in Fig. 1, the paper passing, the gummed side uppermost, in a substantially horizontal path over the said edge and 25 thence downwardly in a substantially vertical plane about a guide and draft roll 13, being bent under tension in its travel at substantially right angles about the breaker 11.

This progressively traveling bend in the 30 paper produces a succession of minute and closely adjacent lines of rupture in the surface of the coating which, though more or less irregular, tend to follow approximately the same direction as the bend. Preferably 35 the paper is subjected to a second breaking action to produce a succession of similar lines of breakage also oblique or inclined to the length of the strip, but lying across or intersecting the first set, so that the 40 gummed coating is broken in two directions both oblique to the length of the strip. This may be accomplished by passing the gummed sheet over a second breaking member similar to the first and producing a similar bend, but reversely inclined with relation 45 to the first bend, so that the resultant lines of breaking intersect those produced by the first breaking action. The paper subjected to this action has its gummed surface broken 50 in two directions by sets of minute closely arranged cracks or breaks which intersect each other, both sets oblique to the length of the paper. The lines of breakage in each set have generally the same direction, 55 although they depart more or less from geometrically straight lines.

The angle along which the breakage takes place in the machine shown in the drawings, is 45° to the edge of the paper, so that each 60 group of breakage lines in the gummed coating is inclined to the length of the paper at an angle of substantially 45° and intersect each other at substantially right angles. This not only simplifies the construction of 65 the machine, but by this method a paper

may be produced either in the form of a continuous sheet or separated separate sheets in which the gummed coating is broken uniformly in both directions with an equal tendency to oppose curling in either direction 70 of its length or width. The grain of the paper ordinarily coincides with the length of the sheet, so that the two sets of breakages are symmetrically located with relation to the grain.

75 My invention, however, broadly contemplates breaking the coating at other angles than 45°, and where paper is treated having greater tendency to curl in one direction than in another, the angle of breakage may be 80 varied to best offset such tendency.

Herein the second breaking action is effected by drawing the paper under tension over a second breaking edge presented by the breaking member 14 (Figs. 1, 2 and 4) the latter supported on the bracket 15 carried on the frame 1. From the guiding and draft roll 13 the paper passes upwardly in a substantially vertical plane direct to the breaking member 14 and thence in a substantially 90 horizontal direction over the said member, the gummed surface being still uppermost and the path of travel of the paper from the breaking edge 14, owing to the relation of the breaking edges and the guiding roll 13, 95 being at substantially right angles to its path of travel from the supply roll to the first breaking member 11.

In the machine shown in the drawings, the 100 breaking member 14 lies in the same plane with the breaking member 11, and is parallel thereto, and the guide and draft roll 13, which has a pitch diameter substantially equal to the space between the breaking members 11 and 14, is inclined at an angle of 45° 105 to the breaking edges. The lower portion of the guide roll is journaled in the lower thrust bearing 15, and the upper portion in the upper bearing 16, both bearings being secured to the framework 1. With this relation of the two breaking members and the inclined guide roll 13, the same tension is maintained in the paper across the entire width of the breaking edge, notwithstanding its angular relation to the paper, and all 110 tendency to climb or creep toward one end of the edge and tear or injure the paper is offset by the angular guiding roll 13.

115 Preferably, though not necessarily, the paper is drawn over both breaking edges by 120 the draft or tension on the paper itself, thus avoiding the use of auxiliary webs. In order to provide the desired and preferably substantially the same tension over both breaking edges 11 and 14, means are herein provided for drawing and tensioning the paper over the breaking edge 11 independent of the means for drawing and tensioning the paper over the breaking edge 14. If the 125 same means were employed for drawing the 130

- paper over the breaking edge 11 as over the edge 14, the tension over the edge 14 would be greater than that over the edge 11 and the tendency would be to cause a more intense breaking over the edge 14.
- 5 While devices might be employed for drawing the paper over the edge 11, independent of the guiding roll 13, such roll herein performs both the function of guiding the paper and also of drawing and tensioning the paper over the breaking edge 11. To effect this, the guide and draft roll 13 is positively driven from any suitable source of power, as by the belt driven pulley 16.
- 10 15 The tension over the breaking edge 14 is independently developed by the friction draft rolls 17 and 18 (Figs. 1 and 4), provided with the intermeshing gears 19, and which may be similar in construction to the frictional rolls 7 and 8 already described. The friction draft rolls 17 and 18 are preferably also independently driven from any suitable source of power such as from the belt driven pulley 20.
- 20 25 The degree of intensity of breakage may be regulated by regulating the tension on the paper, the breakage usually being intensified by increasing the tension. In order to vary the tension to vary the degree of breakage, I may and preferably do provide means for varying the draft or tension on the paper, such means being preferably such that the tension developed by the draft and guide roll 13 may be varied independently 30 35 of that developed by the friction rolls 17 and 18. This provides means whereby the tension and degree of breakage may be regulated to suit varying conditions, such as varying thicknesses of the adhesive coating, changing conditions in the humidity of the atmosphere, and differences in the thicknesses or character of the paper or other conditions. Any suitable means may be provided for effecting the variations in tension, 40 45 50 and herein I have provided for the guide roll 13 a variable friction drive device consisting of the friction roll 21 driven by the pulley 16 in frictional contact with the friction disk 22, the latter connected to positively turn the guide and draft roll 13. The friction roll 21 may be adjusted to different positions across the face of the friction disk 22 to vary the speed of the guide roll by means of the threaded sleeve 23 concentric 55 60 65 with the pulley shaft carrying the hand wheel 24 and passing through a threaded bearing 25. The speed of the friction rolls 17 and 18 is varied by a similar variable friction drive device indicated in Fig. 1.
- 70 75 80 85 90 95 100 105 110 115 120 125 130 0 Ordinarily the speed of the roll 13 and that of the rolls 17 and 18 would be adjusted to equalize the tension over two breaking edges and equalize the intensity of the breaking action, but, if desired to give a greater breaking action over one edge than

over the other, this may be accomplished by varying the speed of these rolls accordingly.

The paper after being subjected to the second breaking action may be utilized in continuous strip form directly in some machine requiring such paper as, for example, a rotary printing press, or the paper may be severed into separated sheets and immediately utilized or stacked for storage, or it may be again wound up in its broken and non-curling condition and stored for future use. Herein I have shown the paper as carried to a suitable winding reel 3 driven by any suitable source of power, not shown, the paper passing from the friction rolls 17 and 18 to the winding roll, over any suitable system of guiding rolls such as the rollers 26 and 27, and an intermediate take-up or tension device. The latter consists of the rollers 28 and 29 between which the paper passes, the rollers being mounted upon an oscillating frame which may be set and maintained at any suitable angle by means of the ratchet and pawl lock, as shown in the drawings. Any suitable guiding and tensioning devices, however, may be employed.

The machine described is capable of breaking gummed paper in the form of a continuous strip with great rapidity and without damage or injury to the paper itself, while its normal output may be greatly increased, if desired, by running two or more superimposed strips of gummed paper through the machine to subject them to a simultaneous breaking action, the paper being unwound from the separate supply rolls and wound onto separate reels after the breaking action has been performed.

The performance of each breaking operation by drawing the paper under tension over a knife edge, renders the breaking effect the same in both directions.

While the action of the machine on the gummed coating produces what is here termed the breaking of the coating, it will be understood that these lines of breakage may be, and usually do appear as, mere minute hair-line surface cracks closely arranged and almost indistinguishable in some cases. These surface cracks will vary as to depth, spacing, number, distribution and location with the thickness of the coating, the thickness of the paper and the character as to brittleness and other qualities of the coating. When the paper is drawn backward over a stationary breaker as described, the bend thus produced travels progressively the entire length of the paper subjecting all parts of the coating to the same progressively advancing line of stress. The coating is thus stretched with its outer surface (where the contracting tendency is greatest) under the maximum stress. Under this traveling line of stress, all parts of the coat-

ing are subject to a uniform breaking effect, but the cracks develop and distribute themselves in the stressed surface exactly where best required to correct the contracting or 5 curling tendency. In some cases the lines may appear where the coating thickens and disappear where the coating becomes thin, reappearing again where the coating again thickens up.

- 10 The cracks develop from the stressed outer surface and work in toward the seat or anchorage of the coating, reaching a depth, however, only sufficient to relieve the stress and oppose the curling tendency. 15 While developing irregularly, they tend to follow the same general direction as the knife edge, but develop where the stress is the greatest and the curling tendency the greatest. The cracks distribute themselves 20 naturally and automatically along regions of greatest stress and where best required to overcome this curling tendency.

While the stressed coating is thus completely broken so far as required, the breakage is developed in both directions under 25 surface stress and there is no tendency to detach or loosen the coating, but the anchorage thereof to the paper may be allowed to remain substantially undisturbed 30 and without such dislodgment as would follow an attempt to break the coating by a beating or impact action. By this described method, therefore, I am enabled to produce a continuous unsevered sheet with 35 the coating broken under surface stress alone and in two directions oblique to the edges of the sheet, with the breakage distributed in a manner to most effectively offset the curling tendency.

40 While I have herein shown and described for the purpose of illustration one specific embodiment of the invention, it is to be understood that the same is not limited to the details or relative arrangement of parts, 45 but that the latter may be widely varied without departing from the spirit of the invention.

Claims.

1. In a machine for breaking the dried 50 coating on thin sheet coated material, the combination with a pair of breakers presenting breaking edges substantially parallel to each other in the same horizontal plane, but with an intervening space, of 55 means for feeding and guiding the sheet material to subject it with the coated side out progressively to the bending action of said breakers in succession, the path of the material from the second breaker being in 60 the same horizontal plane but substantially at right angles to its path to the first breaker, and each breaker being inclined at an angle of 45° to the path of the sheet material, and guiding means between the 65 breakers for guiding the material and pre-

venting creeping on the breakers, the same comprising a guiding roll inclined at an angle of 45° to the breaking edges, the said roll having a diameter equal to the distance between the breakers, thereby guiding the material from the first breaker to the second breaker in substantially parallel vertical planes. 70

2. In a machine for breaking the dried 75 coating on thin sheet coated material, the combination with a pair of breakers presenting breaking edges substantially parallel to each other but with an intervening space, of means for feeding and guiding the sheet material to subject it with the coated side out progressively to the bending action 80 of said breakers in succession, the direction of travel of the material from the second breaker being substantially at right angles to the direction of its travel to the first breaker, each breaker being inclined at an angle to the path of the sheet material, and guiding means between the breakers comprising a guiding roll inclined to the breakers but at right angles to the path of the 85 material.

3. In a machine for breaking the dried 90 coating on thin sheet coated material, the combination with a pair of breakers presenting substantially parallel breaking 95 edges, of means for feeding and guiding the sheet material to subject it with the coated side out progressively to the bending action of said breakers in succession, said breakers being inclined to the path of travel of the sheet material to produce bends respectively inclined in opposite directions to the length of the sheet, and intermediate guiding means inclined to the breakers for guiding the material from one 10 to the other, the plane of the sheet where it approaches the breaker edge being inclined substantially 90° in each case to its plane where leaving the breaker edge.

4. In a machine for breaking the dried 11 coating on thin sheet coated material, the combination with the breakers 11 and 14 substantially parallel to the intermediate guide 13 inclined at an angle of substantially forty-five degrees to the plane of the 11 breakers.

5. In a machine for breaking the dried 12 coating on thin sheet coated material, the combination with a pair of breaking edges lying in substantially the same plane and 12 parallel to each other, of means for feeding the sheet over said breaking edges in succession to produce a sharp bend with the coating outside, and presenting edges at an inclination to the length of the sheet, but 12 one reversely related to the other, said means including guiding means between the breaking edges inclined with relation to the breaking edges, the plane of the sheet where it approaches the breaking edge in each case 13

being inclined substantially 90° to the plane of the sheet where it leaves said breaking edge.

6. A machine for breaking the dried coating on thin sheet coated material, having a plurality of stationary breakers having different inclinations with relation to the length of the material, means for feeding the material over said breakers in succession with 5 the coated side outward, to provide substantially right dihedral angles at the breakers.

7. In a machine for breaking the dried coating on thin sheet coated material, the combination with a plurality of breakers, of 15 means for drawing a continuous strip of said material over said breakers in succession with the coated side outward, and means for developing tension in said material independently for each breaker.

8. In a machine for breaking the dried coating on thin sheet coated material, the combination with a plurality of breakers, of means for drawing the material over said 20 breakers with the coated side outward, and a tensioning device for each breaker.

9. In a machine for breaking the dried coating on thin sheet coated material, the combination with a plurality of breakers, of means for drawing the material over said 30 breakers with the coated side outward, and means for independently regulating the tension of the material at each breaker.

10. In a machine for breaking the dried coating on thin sheet coated material, the combination with a pair of breakers, of means 35 for passing the sheet over said breakers in succession with the coated side out, one of said breakers being inclined obliquely to the length of the sheet, and the other of said 40 breakers being also inclined obliquely to the length of the sheet but at a reverse inclination to the first and the plane of the sheet where it approaches the breaker being inclined in each case at an angle to the plane 45 of the sheet when leaving said breaker.

11. The method of breaking the dried coating of a continuous strip of thin sheet material, which consists in drawing the sheet over a breaking edge diagonal to the direction of travel and maintaining a dihedral angle of 90° between the on-coming and the out-going portion of the sheet.

12. The method of breaking the dried coating of a continuous strip of thin sheet material, which consists in drawing the sheet over a breaking edge inclined approximately 55 at an angle of 45° to the edges of the on-coming portion of the sheet and maintaining a dihedral angle of substantially 90° 60 between the on-coming and the out-going portions of the sheet.

13. The method of breaking the dried coating on thin sheet material characterized by passing the material along the sides of a 65 dihedral angle approximating a right angle,

the edge of which is oblique to the path of travel of the sheet.

14. The method of breaking the dried coating on thin sheet material characterized by passing the material successively along the sides of two dihedral angles approximating right angles, the edges of which are inclined in alternate sense to the path of travel of the sheet. 70

15. In a machine for breaking the dried coating on thin sheet coated material, the combination with a breaker inclined at an angle to the edges of the sheet, of means for drawing a continuous sheet with the coated side out-turned over said breaker, 80 and means to guide the sheet whereby the plane of the sheet in approaching the breaker is inclined at an angle to the plane of the sheet leaving the breaker.

16. In a machine for breaking the dried coating on thin sheet coated material, the combination with a breaker inclined at an angle to the edges of the sheet, of means for drawing a continuous sheet with the coated side out-turned over said breaker, and means 90 to guide the sheet whereby the plane of the sheet in approaching the breaker is inclined at an angle of 90° to the plane of the sheet where leaving the breaker. 95

17. In a machine for breaking the dried coating on thin sheet coated material, the combination with a breaker inclined at an angle of 45° to the edges of the sheet, of means for drawing a continuous sheet with the coated side out-turned over said breaker, 100 and means to guide the sheet whereby the plane of the sheet in approaching the breaker is inclined at an angle of substantially 90° to the plane of the sheet where leaving the breaker. 105

18. In a machine for breaking the dried coating on thin sheet coated material, the combination of a pair of breakers and intermediate guiding means for positioning the material with its length at opposite inclination to the breakers respectively and tensioned over the breakers at dihedral angles approximating right angles, said means arranged differentially to take up the fullness of the sheet between the breakers. 110

19. In a machine for breaking the dried coating on a strip of thin sheet coated material, the combination of means for supporting and guiding the strip for lengthwise travel, a pair of breakers inclined in opposite directions to the length of the strip, said means including mechanism between the breakers differentially to take up the fullness of the strip therebetween and arranged to bend said strip at a dihedral angle over 120 said breakers. 125

20. In a machine for breaking the dried coating on a strip of thin sheet coated material, the combination with a breaker having an edge, of means for drawing the sheet 130

diagonally over such edge, said means being constructed and arranged to cause the entrance angle and the exit angle the sheet makes with a plane including the breaker edge to be constant at all points across the width of the sheet and the sum of said angles at each point to be substantially more than zero degrees.

21. In a machine for breaking the dried 10 coating on a strip of thin sheet coated material, the combination with a pair of breakers having edges, of means for draw-

ing the sheet diagonally over such edges in succession and in opposite senses, said means being constructed and arranged to 15 cause the entrance angles and the exit angles the sheet makes with a plane including a breaker edge to be constant at all points across the width of the sheet, and the sum of the entrance and exit angles at each point 20 to be substantially more than zero degrees.

In testimony whereof, I have signed my name to this specification.

ADOLPH C. VAN SLUYS.
